SIGNALING SYSTEM

Foster E. Weld, Newton, Mass., assignor to The Gamewell Company, Newton Upper Falls, Mass., a corporation of Massachusetts

Application May 5, 1939, Serial No. 271,925

14 Claims. (Cl. 177—354)

The present invention relates to signaling systems, and more particularly to systems of the general type disclosed in the Bridges Patent No. 2,201,712, granted May 21, 1940.

The Bridges patent discloses a multiple circuit repeater system particularly useful for fire alarm service. The system not only affords full non-interfering operation, but has reliable protective facilities for automatically maintaining all normal circuits in operative condition after the occurrence of a break in any circuit. In particular, one feature of the Bridges system is that the protective equipment involves the use of only a single timing relay for the whole system, and normal signaling operation is in no way dependent on the timing relay.

The principal object of the present invention is to provide improvements in the Bridges system with the particular view of maintaining the ability of the system to formulate, transmit and repeat signals, even from a circuit in which a break may exist. In the best form of the invention yet devised a faulty circuit, instead of being isolated from the rest of the system, is automatically conditioned for signaling through an emergency conductor, preferably ground, while the capacity of the system for non-interference is substantially maintained.

Other features of the invention consist of certain novel circuit arrangements hereinafter described and particularly defined in the claims.

In the accompanying drawings Fig. 1 is a diagram of the preferred system in normal inactive condition; Fig. 2 is a diagram similar to Fig. 1 but illustrating the operation of the system during transmission of a signal; and Fig. 3 is a diagram illustrating the emergency conditioning of a faulty circuit.

General description

The invention is herein described as embodied in a repeater type fire alarm system having a number of signaling circuits. For simplicity, only two circuits are shown in the drawings, although the invention is applicable to a system having an number of circuits. The signaling circuits are indicated as box circuits C¹ and C². Those parts of the box circuits which are local to the central station are indicated in double lines in the drawings, and each is connected at terminals, designated "+ Line" and "— Line," to the outlying lines. The lines external to the central station include a number of boxes in series, designated N, of the non-interfering and succession type,

and capable of signaling through ground as will hereinafter be described.

Each box circuit includes a line battery 20 and a normally energized main line relay. The two main line relays are indicated at M¹ and M². Associated with each box circuit are a repeater relay (R¹, R²) and an automatic grounding relay (G¹, G²). Each relay has a number of contacts which are shown in the drawings directly under the corresponding relay winding. Each main relay has seven contacts numbered from 1 to 7, of which contacts 1, 4 and 6 are movable. Contacts 3, 4 and 5 correspond to the main relay contacts of the Bridges patent above referred to, 15 the movable contact 4 being normally closed on contact 3 and adapted to close on contact 5 when the relay M is deenergized. Contacts 1, 2 are normally open and are adapted to close when the relay is deenergized, to control the operation of 20 the grounding relay as will hereinafter be described. Contacts 6 and 7 control the operation of a trouble bell.

Each repeater relay has ten contacts, numbered from 101 to 110, of which contacts 103, 25 104, 108 and 109 are movable. Contacts 106, 107 and 108 correspond to the repeater relay contacts of the Bridges patent. Contacts 101 to 105 are for controlling the operation of the system under abnormal conditions, while contacts 109 and 110 30 are included in the trouble bell circuit.

Each grounding relay has twelve contacts, numbered from 201 to 212, the operation of which will be hereinafter described.

The box circuit C¹ in normal condition is traced 35 as follows: Starting with the positive terminal of the battery 20, the circuit includes the winding of the main line relay M¹, a wire 22 leading to the terminal designated "+ Line," through the series boxes N of the outlying line to the terminal designated "— Line," a wire 24, contacts 107, 106 of the repeater relay R¹, a wire 26, contacts 210, 209 of the grounding relay G¹, and finally a wire 28 back to the negative side of the battery 20.

The movable contact 108 of the repeater relay 45 is connected to a resistor 30, which in turn is connected to the line 22 by a wire 32. As in the above-mentioned Bridges patent, when the repeater relay is energized, contacts 108, 106 are closed and contacts 106, 107 are opened, thereby 50 opening the box circuit and establishing a shunt energizing circuit for the main line relay M¹ through the resistor 30.

The movable contact 4 of the main line relay is connected by a wire 34 with the movable repeater relay contacts 103 and 104, which are

electrically connected together. The fixed contact 105 on which 104 is normally closed, is connected by a wire 36 with a repeater bus RB. The main line relay contact 5 on which contact 4 closes when the relay M' is deenergized, is connected to the positive side of a local battery 37. The local battery serves for all central station connections of the several circuits and its terminals are simply designated by plus and minus signs in circles, the actual connections to the terminals being omitted to avoid complicating the diagram. It will be observed that when the main relay is deenergized, the repeater relay being at the same time deenergized, the positive side of the local battery is connected to the repeater bus through contacts 5, 4, wire 34, contacts 104, 105 and wire 36. These latter connections, as well as the repeater bus RB, constitute a repeater circuit which is shown in heavy lines.

Upon energization, the repeater relay opens the normally closed contacts 104, 105, closes the normally open contacts 101, 103 and opens the normally closed contacts 101, 102. Contact 101 is connected by a wire 38 with one side of the repeater relay winding R', the other side of which is connected to the negative terminal of the local battery. Contact 101 is also connected by a wire 40 with contact 3 of the main line relay.

The grounding relay G¹ is adapted, under abnormal conditions caused by a break in the box circuit, to connect the terminals "— Line" and "— Line" together and to ground the negative terminal of the box circuit battery 28. One side of the grounding relay is connected to the negative terminal of the local battery and the other side is connected by a wire 42 with contact 201. A lamp 44 in parallel to the relay G¹ serves to indicate when the relay is energized. Movable contact 203, which is adapted to close on 201 when the relay G¹ is energized, is connected to the positive terminal of the local battery. Closure of contact 203 on 201 opens contacts 201, 202, the latter being connected by a wire 46 with the fixed contact 204. The movable contact 205 which is adapted to close on 204 when the relay G¹ is energized, is connected by a wire 48 with the fixed contact 102 of the repeater relay. Movable contact 206 connects by a wire 50 with the repeater relay contacts 103 and 104, and the fixed contact 207 on which 206 is normally closed, is directly connected to the wire 36 which connects with the repeater bus.

The normally closed contacts 209, 210 are, as previously described, included in the box circuit. When the relay G¹ is energized, contacts 209, 210 open and 209 closes on 208, the latter being connected to ground as indicated at 52, thus establishing a direct connection between the negative terminal of the line battery 20 and ground. The fixed contact 211 is directly connected to the "— Line" terminal and the movable contact 212 is connected to the wire 32 which connects with the "+ Line" terminal, so that when contacts 211, 212 close, due to energization of the grounding relay, the two terminals of the outlying line are connected together.

Contact 202 is connected by a wire 54 with the movable contact 1 of the main line relay. Contact 2 is connected by a wire 56 with a bus designated as a restore bus X. A trouble bell bus TBB is connected by a lead 58 through contacts 109, 110, a wire 60 and contacts 7, 6 to the positive terminal of the local battery. The bus

includes a bell 62 connected to the negative terminal of the local battery so that the circuit for the bell is closed when contacts 109, 110 and 7, 6 are closed.

5 The second circuit C² and all other box circuits which may be included in the system are identical with the circuit C¹ above described, and are connected to the several busses in the same manner.

10 A single delayed closure timing relay T has its winding connected between the negative terminal of the local battery and the repeater bus RB. The contacts 64 of the timing relay are normally open and are adapted to close only if the timing relay remains energized continuously for greater than a predetermined time, which is adjusted to be longer than the longest time of box circuit opening of any normal signaling operation. When the contacts 64 close, a connection is established between the positive terminal of the local battery and the restore bus X through a lead 66.

15 The system may be provided with suitable signal manifesting devices to operate in the usual manner, illustrated diagrammatically in Fig. 1 as a gong A and a register B connected between the repeater bus RB and the negative terminal of the local battery.

20 The various operations of the system under different conditions will now be described.

System inactive

When the system is in normal condition, all boxes being inactive, each box circuit forms a closed loop and the several main line relays are continuously energized, thus holding their movable contacts attracted. The repeater relays and the grounding relays are deenergized. This condition of the system is shown in Fig. 1.

Box signaling over normal system

During a code signaling operation by an active box in one of the box circuits, say circuit C¹, the circuit is successively opened and closed by the action of the code wheel. Upon the first opening of the circuit by the code wheel, the main line relay M' is deenergized and its movable contacts 1, 4 and 6 retract. The closure of contacts 6, 7 simply operates the trouble bell, and the closure of contacts 1, 2 is of no importance at this time. The closure of contact 5, 4 energizes the repeater relay R² of the box circuit C² as can be seen by following the circuit shown in heavy lines, from the positive terminal of the local battery through contacts 5, 4 of main line relay M', wire 34, contacts 104, 105 of repeater relay R', wire 36, repeater bus RB, thence through wire 36 of circuit C², contacts 105, 104 of repeater relay R² (also contacts 207, 206 of grounding relay G² and wire 50), wire 34, contacts 4, 3 of main line relay M², and wires 40 and 38 through the repeater relay R² to the negative terminal of the local battery. The repeater relay R² of circuit C², being thus energized, attracts its contacts, thereby opening box circuit C² at 106, 107 and establishing a shunt circuit for the main line relay through resistor 30 and contacts 108, 106. The repeater relay R¹ of circuit C¹, however, remains deenergized since the main line relay contacts 3, 4 are now open.

75 The result of opening the box circuit C¹ by the formulation of a signal in the circuit, is that the inactive circuit C² and, in fact, any other inactive box circuits of the system, are likewise opened and the main line relays of the inactive

circuits are maintained energized. This condition of the system is shown in Fig. 2.

Upon closure of circuit C¹ by the normal action of the code wheel of the active box, its main line relay is again energized, the contacts are attracted and the connection between the positive battery terminal and the repeater bus is broken at contacts 4, 5, thereby deenergizing the repeater relay R² of the circuit C² and restoring its contacts to normal. The restoration of the repeater relay contacts of circuit C² also opens the shunt circuit through the resistor 30, and at the same time closes the box circuit. The entire system is thus restored to the condition of Fig. 1.

Subsequent opening and closing of the circuit C¹, due to formulation of a code signal by an active box therein, result in a repetition of the operations above described. All inactive box circuits therefore open and close in unison with the first box circuit to gain control of the system. The boxes are of the non-interfering and succession type, and consequently the entire system is completely free of the possibility of interference between boxes. The particular box construction forms no part of the present invention, since various types of non-interfering boxes may be employed, such boxes usually operating on the principle that a box is unable to formulate a signal if it looks into an open line when its own contacts are closed.

During a code signaling operation, the time relay T and the manifesting devices A and B, being connected to the repeater box RB, are energized on each opening of any box circuit. For any signaling impulse, however, the relay T is not continuously energized for a sufficient time to cause closure of its contacts 64, and the time relay does not enter into any normal signaling operation.

As thus far described, the system operates similarly to the system of the Bridges patent. It will be noted that the repeater relay contacts 101 to 105 correspond to the lockout relay contacts of the Bridges system, but are here combined with the repeater relay instead of being operated by a separate relay. As will be shown presently, these contacts, in combination with the contacts of the grounding relay, operate under abnormal conditions in a fashion similar to the lockout relay contacts of the Bridges system. Under normal signaling conditions, however, the only repeater relay contacts which are effective to perform any function are the contacts 106, 107 and 108. The lockout contacts 101 to 105 of the repeater relay, although they may be attracted and retracted during a normal signaling operation, perform no function. Contact 102 is in series with the normally open grounding relay contacts 204 and 205, while contacts 104 and 105 are in parallel with the normally closed contacts 206 and 207. Thus, so long as the grounding relay remains deenergized, any operation of contacts 101 to 105 is unimportant.

Operation of protective devices

The occurrence of a break in any box circuit does not disable the system, but permits all except the faulty box circuit to be restored to normal, and also converts the faulty circuit for emergency signaling through ground. This operation is described as follows:

Upon a break in circuit C¹, for example, its main line relay M' is deenergized and the repeater relays of all inactive circuits are ener-

gized in the same manner as if the circuit were opened by an active box. The system then assumes the condition of Fig. 2. After a predetermined time, however, the timing relay allows its contacts 64 to close, thereby connecting the positive terminal of the local battery with the restore bus X through the lead 66. The grounding relay G' of circuit C' is therefore energized through the following circuit: from the positive terminal of the local battery, through contacts 64, lead 66, restore bus X, wire 56 of circuit C', main line relay contacts 2, 1, wire 54, contacts 202, 201 of relay G', wire 42, and the winding of relay G' to the negative terminal of the battery. Energization of the grounding relay occurs only for circuit C'. The grounding relay G² of circuit C² is not energized because the main line relay contacts 1, 2 of that circuit are open.

When the grounding relay G' is energized, its movable contacts 203, 205, 206, 209 and 212 are attracted and, as previously described, the negative side of the battery 20 is connected to ground through contacts 209, 208, and the positive and negative terminals of the line are connected together through contacts 211, 212. Thus, the box circuit C' now consists of two outlying lines, each running to the break.

When the grounding relay G is energized, a holding circuit is established from the positive side of the local battery through contacts 203, 201 and at the same time contacts 202, 201 are opened.

Energization of the grounding relay G' results in energization of the repeater relay R' of the faulty box circuit. Bearing in mind that the positive potential of the local battery is applied to contact 202 through the circuit previously traced, a circuit may now be continued from contact 202 through lead 46, contacts 204, 205, wire 48, contacts 102, 101 of the repeater relay R', and wire 38 through the repeater relay winding to the negative local battery terminal. Contacts 204, 205 might be omitted and the wire 46 might be connected direct to contact 102, so that relays R' and G' would be simultaneously energized, except that it is desirable to insure that G' shall energize before R'; if R' should pick up its contacts first, the main line relay might be energized through the shunt resistor 30 before G' could open the circuit at 209, 210. Energization of the repeater relay opens contacts 102, 101, but a holding circuit for the repeater relay is established from the positive battery terminal, through contacts 5, 4 of the main line relay M', wire 34 and contacts 103, 101 of the repeater relay. As a result of the energization of the repeater relay, contacts 106, 108 are closed and contacts 106, 107 are opened, but this is of no importance since the box circuit loop is already open at contacts 209, 210.

Since both the repeater relay R' and the grounding relay G' are now energized, the heavy line circuit from the positive terminal of the local battery to the repeater bus RB is broken at contacts 206, 207 and 104, 105. As a consequence, the repeater bus is no longer energized, the repeater relay R² becomes deenergized, and the inactive box circuit C² is restored to normal. At the same time the timing relay T is deenergized and its contacts are allowed to open.

Another effect of the energization of the repeater relay R' is to open the trouble bell circuit at contacts 109, 110.

The condition of the system following the operation above described is illustrated in Fig. 3. It

will be observed that the lockout contacts 101 to 105 of the repeater relay R' perform the same general function as the lockout relay contacts of the Bridges system, namely, that of isolating the main line relay contacts of the faulty circuit from the repeater bus, so that the faulty circuit can neither affect, nor be affected by the repeater connection. This action occurs only because the grounding relay G' is also energized, so that the connection 36 is broken both at contacts 207, 206 and 105, 104. The correlation of grounding relay and repeater relay contacts thus makes it possible to combine the repeating, lockout and grounding functions into two relays. In spite of the fact that the system is adapted for automatic emergency conditioning, the number of relays is thus held to three for each circuit.

It is to be noted that the isolation of the faulty circuit C' from the repeater bus occurs only during continued deenergization of the main line relay M', since the holding circuit for R' is carried through contacts 4, 5. As will be shown presently, when the relay M' becomes energized, as at the start of a ground signaling operation, the faulty circuit is no longer isolated from the system.

Box signaling over the system conditioned as shown in Fig. 3

When the system is conditioned as in Fig. 3, due to operation of the grounding relay on a faulty box circuit, the normal box circuit C² and any other normal box circuits of the system stand ready to originate and transmit signals, and to repeat among themselves in exactly the same manner as described for the normal system of Fig. 1. For example, a signal originating in circuit C² controls the repeater relays of all other normal circuits through the repeater bus RB.

The timing relay stands ready to control the emergency conditioning of circuit C² or any other circuit which may subsequently become faulty. All normal circuits, therefore, stand in the same relation to each other as if the faulty circuit were non-existent.

It is now necessary to consider the relations between the faulty circuit and the normal circuits, and this will be done by describing, first, the effect on a normal circuit of a signal originating in the faulty circuit, and, second, the effect on the faulty circuit of a signal originating in a normal circuit.

Assume first that with the system as shown in Fig. 3, a box in the faulty circuit C' starts to formulate a signal. The boxes are of a type to transmit emergency signals through ground, for which purpose several types of boxes are available. The preferred type of box is the so-called three-fold box described in the Beach Reissue Patent 20,449, which includes means for testing the line and establishing an emergency ground signaling connection on the second round, if the line is found to be open. Whatever type of box is employed, a connection is first established to ground prior to the signal formulating operation. A closed circuit may now be traced from ground through wire 52, contacts 208, 209 of the grounding relay G', wire 28, battery 20, main line relay M', wire 22, to terminal "+ Line," wire 32 and contacts 212, 211 of relay G' to the terminal "- Line," then from one or the other of the line terminals to the box, and finally to ground at the box. The main line relay M' is then energized and its contacts are attracted, thereby breaking the holding circuit for the repeater

relay R' at the contacts 4, 5. On subsequent opening and closing of the ground signaling circuit through the action of the code wheel, the main line relay is successively deenergized and reenergized in exactly the same manner as if the signal were being transmitted over a normally closed loop. The repeater relay R', having been deenergized by the breaking of its holding circuit, remains deenergized during the entire signaling operation. Therefore, upon each deenergization of the main line relay, due to opening of the ground signaling circuit by the action of the code wheel, the connection between the positive terminal of the local battery and the repeater bus RB is established through contacts 5, 4, wire 34, contacts 104, 105, and connection 36, just as in the case of normal signaling. Accordingly, signals originating from any box in the faulty circuit are repeated over all normal box circuits in the system and thus interference with any active box in circuit C¹ by a box in any other circuit is prevented.

At the conclusion of the signal the ground connection at the box is broken and the main line relay is deenergized. It is now necessary to re-energize the repeater relay R' in order to permit all normal box circuits to be restored to normal condition. This is accomplished by the action of the timing relay operating through the restore bus X. In other words, the timing relay and the repeater relays of the several circuits go through the same operations as they did immediately following the detection of the break in the faulty box circuit. The grounding relay G' of the faulty circuit remains energized throughout, because of the holding circuit established at contacts 201, 203.

Assume now that with the system in the condition of Fig. 3, a box in the normal circuit C² starts to formulate a signal. In this case there is no effect on the faulty circuit C¹ because the connection 36 for circuit C¹ which leads from the repeater bus RB terminates on the open contacts 207 of the grounding relay G' and 105 of the repeater relay R'. Hence, while a signal originating in the faulty circuit can repeat into all normal circuits, the reverse is not true and a signal originating in a normal circuit cannot repeat into the faulty circuit. Interference will, therefore, occur if a box in the faulty circuit is pulled while a box in a normal circuit is transmitting a signal. This contingency is remote and even if it does occur, it will ultimately result in circuit C¹ taking control of the system, even though there may be some initial jumbling of the signals. This follows from the general proposition that a box or circuit having good non-interference characteristics will lose control to a box or circuit of poorer non-interference characteristics; that this proposition holds in this specific case may be seen by considering that in the normal operation of the code wheels a time must come when the main line relay M¹ is deenergized and the main line relay M² is energized. At such a time the repeater circuit to the repeater relay R² is closed and the energization of the repeater R² under such circumstances results in opening the box circuit C² and thus cuts the active box of circuit C² out of further participation. It will be noted that circuit C² is unable to prevent circuit C¹ from gaining control even at a time when relay M² is deenergized and relay M¹ is energized, because the consequent energization of repeater relay R¹ has no effect on circuit C¹. The result

is therefore that the box in the faulty circuit takes control at some time in the round. One round may be jumbled, but a clear signal is thereafter transmitted by the active box in the faulty circuit. After such box has completed its signal the system is restored to the condition of Fig. 3 through the operation of the timing relay, and thereafter the waiting box in the normal circuit, if it is of the succession type, will formulate and transmit its own signal.

The foregoing method of operation is considered the preferred method, in spite of the possibility of jumbled signals under unusual circumstances. If desired, however, the faulty circuit may be effectually isolated from the remainder of the system by providing a manual switch 63 in each lead 36. After a box circuit has been found faulty, the switch 63 may be opened manually, thus making it impossible for the faulty circuit to affect or to be affected by any of the other circuits. It is, however, considered preferable to allow the faulty circuit to participate in the operation of the system as a whole, even at the risk of occasional jumbling, than to isolate the faulty circuit from the rest of the system.

Restoration of circuit after repair

After the break in the faulty box circuit has been repaired, the circuit is restored to its normal loop condition manually, by momentarily opening a switch 68 in series with the contact 203 of the grounding relay G'. This opens the holding circuit and deenergizes the grounding relay. Movement of contact 209 to 210 and of 211 to 212 closes the circuit of the main line relay M' through the shunt resistor 30, it being understood that contacts 106, 108 are now closed and contacts 106, 107 are open, due to energization of the repeater relay. Consequently, the main line relay is energized through the shunt resistor 30 and its contacts are attracted. The attraction of the main relay contacts breaks the holding circuit for the repeater relay at 4, 5. The repeater relay then becomes deenergized, and the circuit is restored to the normal condition shown in Fig. 1.

It will be noted that on opening the manual switch 68, contacts 206, 207 of the grounding relay will close before contacts 5, 4 of the main line relay open. A connection is then momentarily established from the positive terminal of the local battery through contacts 5, 4, wire 34, wire 50, contacts 206, 207 and wire 36 to the repeater bus. This momentary connection will tend to cause the repeater relays of normal circuits to be energized and give a stroke on the system. To prevent this, a switch 70 is preferably included in the lead 63 and is adapted to be opened simultaneously with the manual switch 68.

Conclusion

From the foregoing description it will be seen that the system is in general similar to that of the Bridges patent, in that perfect non-interference between normal circuits is obtained.

Furthermore, the reliability of the system is enhanced by the provision for automatic emergency conditioning of a faulty circuit, instead of rendering such circuit inoperative. This result is attained without serious loss of non-interfering characteristics, since as previously described, the only possibility of interference arises when a box in the faulty circuit starts to operate dur-

ing a signal formulation by a box in a normal circuit.

As in the Bridges system, the protective devices have the important advantage of being dependent on a single timing relay which in no way enters into any signaling operation. Failure of the timing relay or its connections can result only in a loss of protective function and cannot deprive the signaling circuits, so long as they are in normal condition, of their ability to signal and repeat in normal fashion.

Although the invention has been illustrated and described as embodied in a fire alarm system, it is to be understood that the invention is not thus limited, but may be applied to signaling systems for other purposes. Furthermore, the invention is not to be considered as limited to the particular embodiment shown and described but may be modified within the scope of the claims.

Having thus described the invention, I claim:

1. A signaling system having in combination a plurality of normally closed signaling circuits each having a normally energized main line relay, repeater means for the several circuits, a grounding relay for each signaling circuit to condition the circuit for emergency ground signaling, timing means acting upon deenergization of a main line relay for a predetermined time to operate the grounding relay of the corresponding circuit, and lockout means operated by the timing means to isolate said circuit from the repeater means during continued deenergization of the main line relay.

2. A signaling system having in combination a plurality of normally closed signaling circuits each having a normally energized main line relay, repeater means for the several circuits, a grounding relay for each signaling circuit to condition the circuit for emergency ground signaling, timing means acting upon deenergization of a main line relay for a predetermined time to operate the grounding relay of the corresponding circuit, a lockout device for each circuit, and connections between the timing means and the lockout devices to isolate an abnormal circuit from the repeater means during continued deenergization of the main line relay.

3. A signaling system having in combination a plurality of normally closed signaling circuits each having a normally energized main line relay, repeater means for the several circuits, a grounding relay for each signaling circuit to condition the circuit for emergency ground signaling, a single timing relay for the several circuits operable upon deenergization of any main relay for a predetermined time, a lockout device for each circuit, and connections between the timing relay, the grounding relays and the lockout devices to energize the grounding relay of an abnormal circuit and also to isolate the abnormal circuit from the repeater means during continued deenergization of the main line relay.

4. A signaling system having in combination a plurality of normally closed signaling circuits each having a normally energized main line relay, a repeater relay for each circuit, a repeater bus connecting the main line relays and repeater relays of the several circuits, a grounding relay for each circuit to condition the circuit for emergency ground signaling, timing means acting upon deenergization of a main line relay for a predetermined time to operate the grounding relay of the corresponding circuit, and lockout means operated by the timing means to isolate

said circuit from the repeater bus during continued deenergization of the main line relay.

5. A signaling system having in combination a plurality of normally closed signaling circuits each having a normally energized main line relay, a repeater relay for each circuit, a repeater bus connecting the main line relays and repeater relays of the several circuits, a grounding relay for each circuit to condition the circuit for emergency ground signaling, a single timing relay for the several circuits operable upon deenergization of any main line relay for a predetermined time, a lockout device for each circuit, and connections controlled by the time relay to operate the grounding relay and also, during continued deenergization of the main line relay, to isolate the abnormal circuit from the repeater bus.

6. A signaling system having in combination a plurality of normally closed signaling circuits each having a normally energized main line relay, a repeater relay and a grounding relay for each signaling circuit, each grounding relay having provision for converting its circuit for emergency ground signaling, a repeater circuit, timing means operating upon de-energization of a main line relay for a predetermined time for operating the grounding relay of its circuit, while leaving the other circuits in normal condition, and lockout means for isolating a faulty signaling circuit from the repeater circuit.

7. A signaling system having in combination a plurality of normally closed signaling circuits each having a normally energized main line relay, a repeater relay and a grounding relay for each signaling circuit, each grounding relay having provision for converting its circuit for emergency ground signaling, a repeater circuit, a single timing device for the several circuits, connections between the timing device and the grounding relays to operate the grounding relay of any circuit for which the main line relay remains de-energized for a predetermined time, and lockout means for isolating a faulty signaling circuit from the repeater circuit.

8. A signaling system having in combination a plurality of normally closed signaling circuits each having a normally energized main line relay, a repeater relay and a grounding relay for each signaling circuit, each grounding relay having provision for converting its circuit for emergency ground signaling, a repeater circuit, the main line relays having contacts connecting with the repeater circuits, lockout means for opening the connections between the several main line relay contacts and the repeater circuit, and timing means operated upon deenergization of a main line relay for a predetermined time for operating the grounding relay and lockout means of the corresponding signaling circuit.

9. A signaling system having in combination a plurality of normally closed signaling circuits each having a normally energized main line relay, a repeater relay for each signaling circuit having contacts to open its signaling circuit, a repeater bus, each main line relay having a contact connected with its corresponding repeater relay and a contact connected with the repeater bus, lockout means for opening the connection between the main line relay contact and the repeater bus, time actuated means, additional main line relay contacts, and connections from the time actuated means through the additional main line relay contacts to operate the lockout means for any circuit for which the main line relay remains open for a predetermined time.

10. A signaling system having in combination a plurality of normally closed signaling circuits each having a normally energized main line relay, repeater devices controlled by the signaling circuits, a grounding device for each circuit operable to condition an open signaling circuit for emergency ground signaling, a time relay having contacts to operate only after an abnormal signaling circuit remains open for a predetermined time, lockout means for each circuit, and connections including the time relay contacts to operate the grounding device of an abnormal circuit, said connections having provision for operating the lockout means of the abnormal circuit to render the abnormal circuit ineffective to control the repeater devices during continued deenergization of the main line relay of the abnormal circuit.

11. A signaling system having in combination a plurality of normally closed signaling circuits each having a normally energized main line relay, repeater devices controlled by the signaling circuits, a grounding device for each circuit operable to condition an open signaling circuit for emergency ground signaling, a time relay having contacts to operate only after an abnormal signaling circuit remains open for a predetermined time, lockout means for each circuit, connections including the time relay contacts to operate the grounding device of an abnormal circuit, said connections having provision for operating the lockout means of the abnormal circuit to render the abnormal circuit ineffective to control the repeater devices during continued deenergization of the main line relay of the abnormal circuit.

12. A signaling system having in combination a plurality of normally closed signaling circuits each having a normally energized main line relay and a repeater relay, repeater connections for actuating the repeater relays of inactive box circuits, a grounding relay and lockout means for each circuit, a timing relay having contacts actuated only by the deenergization of the main line relay of an abnormal signaling circuit for a predetermined time, connections including the time relay contacts to operate the grounding relay and the lockout means of the abnormal circuit, the lockout means having provision for isolating the abnormal circuit from the repeater connections only during continued deenergization of the main line relay of the abnormal circuit.

13. A signaling system having in combination a plurality of normally closed signaling circuits each having a normally energized main line relay and normally deenergized repeater and grounding relays, the grounding relays being operable when energized to convert their corresponding circuits for emergency ground signaling, repeater connections for actuating the repeater relays of inactive signaling circuits, lockout contacts for each repeater relay to isolate the corresponding signaling circuit from the repeater connections when the repeater relay is energized, a timing relay having contacts actuated upon deenergization of a main line relay of an abnormal circuit for a predetermined time, connections including the time relay contacts for energizing the grounding and repeater relays of the abnormal circuit, and means for holding the repeater relay of the abnormal circuit ener-

gized only during continued deenergization of the corresponding main line relay.

14. A signaling system having in combination a plurality of normally closed signaling circuits each having a normally energized main line relay and normally de-energized repeater and grounding relays, the grounding relays being operable when energized to convert their corresponding circuits for emergency ground signaling, a repeater circuit, each main line relay having a contact connected with the repeater circuit, lockout contacts for each repeater relay to open the said connection of said main line

relay contact with the repeater circuit when the repeater relay is energized, a time relay having contacts actuated upon de-energization of a main line relay of an abnormal circuit for a predetermined time, connections including the time relay contacts for energizing the grounding and repeater relays of the abnormal circuit, and means for holding the repeater relay of the abnormal circuit energized only during continued de-energization of the corresponding main line relay.

FOSTER E. WELD.

CERTIFICATE OF CORRECTION.

Patent No. 2,250,922.

July 29, 1941.

FOSTER E. WELD.

It is hereby certified that error appears in the printed specification of the above numbered patent requiring correction as follows: Page 1, first column, line 46, for the word "an" read --any--; page 2, first column, line 34, for " "—Line" " read --" +Line"--; and that the said Letters Patent should be read with this correction therein that the same may conform to the record of the case in the Patent Office.

Signed and sealed this 14th day of October, A. D. 1941.

(Seal)

Henry Van Arsdale,
Acting Commissioner of Patents.
